UNITED STATES PATENT OFFICE.

THOMAS E. WASHBURN, OF COALINGA, CALIFORNIA.

COMPOSITE-PICTURE DEVICE.

1,064,576.

Specification of Letters Patent. Patented June 10, 1913.

Application filed August 23, 1912. Serial No. 716,728.

To all whom it may concern:

Be it known that I, THOMAS E. WASHBURN, a citizen of the United States, residing at Coalinga, in the county of Fresno and State of California, have invented new and useful Improvements in Composite-Picture Devices, of which the following is a specification.

This invention provides an appliance of 10 novel structure which admits of the presentation of a picture or other outline in such a manner as to admit of one or more of the parts being interchanged or substituted by other parts so as to change the general character 15 of the representation or picture.

Specifically considered the invention has relation to a device comprising a plurality of rotary members, each of the members being provided with complementary parts of 20 pictures or other representations so that relative movement of the members bring the parts of the picture or representation into matching relation to produce a composite picture which may be varied at will.

25 The device consists of a casing having an observation opening, a plurality of rotary members arranged within the casing in axial alignment and adapted to be rotated to bring them into any desired relative position, said 30 members having parts of pictures or other representation thereon in such relation as to admit of the parts matching to produce a composite picture or representation, and means whereby the rotary members may be 35 conveniently turned from a point exterior to the casing.

The invention consists of the novel features, details of construction and combination of parts, which hereinafter will be more 40 particularly set forth, illustrated in the accompanying drawings, and pointed out in the appended claim.

45 Referring to the drawings, forming a part of the specification, Figure 1 is a side view of a composite picture device embodying the invention. Fig. 2 is a vertical central section thereof. Fig. 3 is a view in elevation of the rotary members removed from the casing. Fig. 4 is a detail view of the several 50 rotary members separated and relatively disposed in a group.

55 Corresponding and like parts are referred to in the following description, and indicated in all the views of the drawings, by the same reference characters.

Within the purview of the invention it is

to be understood that the device may comprise any number of rotary members and that the same may be of any form and provided with any matter depending upon the 50 character of the representation or picture to be produced. As illustrated three rotary members are employed and are indicated respectively by the numerals 1, 2 and 3. The rotary members are arranged in line so as to 55 rotate about an axis common to all. For the sake of convenience the rotary member 1 is designated as the upper or top member, the member 2 as the middle member and the member 3 as the lower or bottom member, 60 said members bearing parts corresponding with the representation of the human figure, the upper member bearing the representation of a plurality of heads, the middle member the representation of the body 65 and the lower member the representation of the feet and legs. These several representations are designed so as to match and provide a composite figure. It will thus be 70 understood that by moving the member 1 75 any one of the heads appearing thereon may be brought into position to match with the remaining portion of the figure, thereby changing the general character. The same effect may be produced by moving either the 80 middle member or the bottom member or both. It is thus possible to produce a variety of pictures, each having a different appearance from the other. It is to be understood that the matter appearing on the 85 rotary members may be of any nature according to the representation to be disclosed.

The casing 4 is provided in a side with an observation opening 5 which extends lengthwise thereof, the edge portion of the 90 material comprising the casing bordering upon the opening being bent inwardly to give a finished appearance. A step 6 is provided upon the bottom of the casing to receive the lower end of the stem 7 having 95 the bottom member 3 attached thereto, said stem projecting through an opening in the top of the casing and having a button 8 at its upper end.

The rotary member 2 is provided with 100 a hollow stem 9 which projects a short distance below the lower side of the member to rest upon the member 3 and thereby space the two members 2 and 3. The stem 9 receives the stem 7 and likewise projects 105 through the opening in the top of the casing and has a button 10 at its upper end.

The lower side of the member 2 is recessed to receive the upper portion of the member 3. The upper side of the member 2 is likewise recessed to receive the lower portion of the member 1, which is placed thereon and supported by means of a stem 11 fitted thereto. The stem 11 is hollow and receives the stem 9 and its lower portion projects slightly below the member 1 to space it from the member 2. The upper end of the stem 11 projects through the opening in the top of the casing 4 and has a button 12 fitted thereto. The buttons 8, 10 and 12 are of different diameters and are located at different levels, thereby admitting of any one being conveniently grasped for manipulating the desired member to bring the part of the picture or representation thereon in position to register 20 with the remaining parts of the picture or representation on the other members.

From the foregoing description, taken in connection with the accompanying drawings, the advantages of the construction 25 and of the method of operation will be readily apparent to those skilled in the art to which the invention appertains, and while I have described the principle of operation of the invention, together with 30 the device which I now consider to be the best embodiment thereof, I desire to have it understood that the device shown is

merely illustrative, and that such changes may be made when desired as are within the scope of the claim appended hereto. 35

Having thus described the invention what is claimed as new, is:—

A device for exhibiting a composite picture, the same comprising a casing having a side observation opening, rotary members 40 mounted within the casing in axial alignment, each bearing on its circumference corresponding parts of the figure to be displayed and so arranged as to admit of the matter upon any one of the members being brought into position to register with the matter on the remaining members to produce a composite whole, and stems having connection with the respective members and having a concentric arrangement and 50 projecting to different distances beyond the casing and provided at their projecting ends with thumb pieces, the said rotary members having the meeting face of one recessed to receive the meeting face of the 55 other to hold the several members in fixed position.

In testimony whereof I affix my signature in presence of two witnesses.

THOMAS E. WASHBURN.
